UNITED STATES PATENT OFFICE

104,630

DESIGN FOR A HANDLE FOR A CASKET OR ANALOGOUS ARTICLE

Raymond Larson, Chicago, Ill., assignor to Central Metallic Casket Co., Chicago, Ill., a corporation of Illinois

Application November 6, 1936, Serial No. 65,737

Term of patent 7 years

To all whom it may concern:

Be it known that I, Raymond Larson, a citizen of the United States, residing at 2207 North Lamon Avenue, Chicago, in the county of Cook and State of Illinois, have invented a new, original, and ornamental Design for a Handle for a Casket or Analogous Article, of which the following is a specification, reference being had to the accompanying drawing, forming part thereof:

Figs. 1 and 2 are respectively, a front elevation

and a top plan view of a handle for a casket embodying my new design, the portions of the figures shown in dot and dash lines being similar in design to those shown in full lines; and

Fig. 3 is an end elevational view of same.

I claim:

The ornamental design for a handle for a casket or analogous article as shown and described.

RAYMOND LARSON.
